[57] CLAIM

I claim the ornamental design for chandelier, as shown and described.

DESCRIPTION

FIG. 1 is a side elevational view of the chandelier of my new design;

FIG. 2 is a top plan view of the chandelier of FIG. 1;

FIG. 3 is a perspective view of the chandelier of FIG. 1;

FIG. 4 is a front elevational view of the chandelier of FIG. 1;

FIG. 5 is a side elevational view of an alternate embodiment of the chandelier of my new design;

FIG. 6 is a top plan view of the chandelier of FIG. 5;

FIG. 7 is a perspective view of the chandelier of FIG. 5; and,

FIG. 8 is a front elevational view of the chandelier of FIG. 5.
